UNITED STATES PATENT OFFICE.

HENRY I. PERSELS, OF SANDUSKY, MICHIGAN.

HOLDBACK FOR HARNESS.

No. 906,156.

Specification of Letters Patent.

Patented Dec. 8, 1908.

Application filed June 27, 1908. Serial No. 440,730.

To all whom it may concern:

Be it known that I, HENRY I. PERSELS, a citizen of the United States, residing at Sandusky, in the county of Sandusky and State of Michigan, have invented certain new and useful Improvements in Holdbacks for Harness, of which the following is a specification.

This invention relates to hold-backs for harness, and has for its object to provide an improved means for attaching the hold-back straps to the thills of the vehicle.

The invention is illustrated in the accompanying drawings, in which—

Figure 1 is a side view illustrating the invention; Fig. 2 is a top view; and Fig. 3 is an end view.

Referring specifically to the drawings, 6 indicates the vehicle thill. This is provided 10 with a metallic stop or catch 7 consisting of a piece of iron or other metal bent to form one arm which is attached by screws or otherwise to the under side of the thill, and to form a lower prong or projection with a shoulder which acts as a catch and stop for the thill loop 8 which is buckled to the back band and which supports the thill.

To each side of the thill loop or carrier is sewed one end of a folded strap 9 which 20 is stitched near the fold as at 10 forming an eye 11 which receives the metal loop 12 to which the breeching 13 is connected.

The iron catch stop on the under side of the thill is put on for the purpose of holding 30 the thill loop in place, and it forms a stop for said loop when the horse is backing. In hitching or unhitching, the loop can be slipped off the thill without unfastening any buckles, and in much less time than is usually required to disconnect the ordinary hold-back 40 straps which are wrapped around the thill.

The device is neat in appearance and holds the harness together in such shape that it can be readily put on or taken off the horse, and there are no hanging straps for the horse to tread on. The arrangement is also safer, because when the tugs are unhitched, the horse can walk out of the thills with no danger of dragging the vehicle by the hold-back straps.

The folded strap 9, which is connected at its ends to the opposite sides of the thill loop, gives an even pull on both sides of the loop and hence avoids twisting of the loop, and makes the breeching draw on a level, 50 and in line with the thill, and it does not draw down on the breeching nor up on the belly-band. The catch on the under side of the thill is not noticeable especially, and can be used on a thill of any size, and can be 55 moved from one thill and placed on another when desired. The attachment on opposite sides of the thill loop also avoids twisting of the back strap, which would be apt to occur in case of attachment at one side only. 60

The device has the advantage of cheapness, and it can be applied to any ordinary harness by setting the ends of the strap 9 in the thill loop.

I claim:

A hold-back for harness comprising a thill loop adapted to extend around the thill, and a breeching strap having branches connected at their ends to the loop on opposite sides of the thill respectively and in horizontal alinement therewith.

In testimony whereof I affix my signature in presence of two witnesses.

HENRY I. PERSELS.
